UNITED STATES PATENT OFFICE

135,716

DESIGN FOR AN AIRCRAFT RECOGNITION CARD DECK

Robert G. Willard, United States Navy,
Washington, D. C.

Application December 28, 1942, Serial No. 109,147

Term of patent 3½ years

To all whom it may concern:

Be it known that I, Robert G. Willard, a citizen of the United States, residing at Washington, D. C., have invented a new, original, and ornamental Design for an Aircraft Recognition Card Deck, of which the following is a specification, reference being had to the accompanying drawings, forming a part thereof.

Figs. 1 to 6, inclusive, are plan views of the deck of cards, showing my new design.

The backs of the cards are conventional.

I claim:

The ornamental design for an aircraft recognition card deck, as shown and described.

ROBERT G. WILLARD.
